UNITED STATES PATENT OFFICE.

ALFRED G. F. KUROWSKI, OF BROOKLYN, NEW YORK, ASSIGNEE TO UNDERWOOD TYPEWRITER COMPANY, OF NEW YORK, N. Y., A CORPORATION OF DELAWARE.

TYPEWRITING MACHINE.

Application filed September 4, 1935. Serial No. 54,451.

This invention relates to multiple-web typewriting machines, and is illustrated herein as applied to an Underwood combined typewriting and computing machine.

5 In machines of this character, a composite pack, comprising web-plies interleaved with carbons, is fed downward along a rear paper-table, around the platen, and brought up to typing position over a front work-table. 10 It is also usual in such machines to keep in place around the platen permanently a record-sheet to accumulate carbon-copies of all the items which are typed upon successive sections of the web-plies, the typed sections 15 being torn off one after another upon completion, and a carbon-carrying frame mounted at the rear of the machine is operable to strip the carbons from the completed sections of the web-plies after the platen has 20 been swung to an elevated position above the carriage to straighten the composite pack beneath the platen. During such elevation of the platen it is necessary to hold the record-sheet against displacement, which may 25 result through manipulation of the carbons and web-plies during the stripping operation.

One of the features of the present invention is the provision of a clamping device 30 for holding the record-sheet stationary during the above-noted carbon-stripping operation. The device is arranged to automatically clamp the record-sheet under pressure upon release of the usual finger-piece, which 35 holds the platen in normal position within the platen-carriage.

Another feature of the invention is the provision of a combined guide and paper-table for guiding the leading edge of the 40 record-sheet upwardly adjacent the rear of the platen, in order to properly guide the record-sheet under the clamping device and toward the rear of the machine and prevent any tendency of said record-sheet from 45 winding itself around the platen during the feeding of the work-plies. The record-sheet is introduced into the machine between the usual cutting-off knife and the platen, while the platen is in elevated position, and a guide 50 is provided for directing the leading edge of the record-sheet around the platen to meet the combined paper-guide and table, which then causes the leading edge to be deflected away from the platen. During this operation 55 the record-sheet clamp is released by

means of a suitable finger-piece forming a portion of the clamp.

Another feature of the invention is the provision of a novel tie-bar or bridge-piece, connecting the usual side plates of the 60 platen-elevating frame. In addition to rigidly tying the side plates together, the tie-bar provides a support for the front work-table, the record sheet clamp, record-sheet guiding fingers, and the combined paper-guide and table, thus all of the parts are 65 combined and supported as a unit.

Other features and advantages will hereinafter appear.

In the accompanying drawings,

Figure 1 is a vertical section through the platen-carriage and a portion of the computing mechanism of a combined typewriting and computing machine, showing the record-sheet in position around the platen 75 and a clamping device released.

Figure 2 is a similar view showing the clamping device effective.

In Figure 3 the platen has been elevated and a record-sheet is being inserted there- 80 around with the clamp released.

Figure 4 is a view similar to Figure 3, showing the clamp applied and the web being brought to position against a leading edge gage.

Figure 5 is a disassembled view in perspective of the various parts forming a tie-bar, guide-fingers, supporting means for the record-sheet clamp, and paper-tables, etc.

Figure 6 is a plan view of the tie-bar and 90 platen, portions being illustrated in section.

Figure 7 is a plan view of the mechanism illustrated in Figure 4, the platen-frame being swung to elevated position.

Referring particularly to Figure 1 of the 95 drawings, the reference numeral 10 indicates a composite pack of web-plies and carbons, the plies being fed upward from the rear of a combined typewriting and computing machine 11, a portion of the computing mechanism being indicated at C. The pack is led forward over the usual track or extension 12 and between side edge guides 13 and thence downward over a rear paper-table 14 and around a platen 15 to the printing line, to receive type-impressions of the types 16. The leading edges of the pack are led 100 upward between a cutting-off knife 17 and the platen, and thence over a front paper-table 18 in the usual way, and feed-rolls 19. 105 110

co-operate with the platen in feeding the webs therearound. There is provided on each of the ends of the platen-shaft 20, a gear 21, which meshes with a wide pinion 22 mounted on a stud-shaft 23 in each of the end frames 24 of the platen-carriage 25, the platen being mounted in a swing-frame 26 including a pair of end plates 27 pivoted at 28 to each of the end frames 24 of the platen carriage. Gears (not shown) similar to the gears 21 mesh with each wide pinion 22 and each gear is mounted upon a short shaft rotatable in each carriage end and in axial alignment with the platen-shaft 20, each of said shafts being provided with a hand-wheel (not shown), so that when the platen is locked in normal position against the feed-rolls 19, each hand wheel may be utilized to rotate the platen through the medium of either pinion 22 and a gear 21. An example of such gearing is illustrated in Patent No. 1,465,789 to H. L. Pitman, granted August 21, 1923. It will be seen upon elevating the platen 15 by raising the swing-frame 26 that each gear 21 will roll out of mesh with its pinion 22. A stop 29 adjacent the pivot 28 of the swing-frame 26 rests upon a portion of the machine 11 to determine the elevated position of the platen 15.

It is usual in combined typewriting and computing machines to type simultaneously with the web-plies a record-sheet which is kept in place around the platen permanently, that is, until all the available writing area thereof has been exhausted. In the drawings the reference numeral 30 indicates such record-sheet, which has been led down over the pack 10 around the platen and under the pack up to the printing line, and thence deflected rearwardly by means of a guide-finger 31 disposed adjacent the top of the platen. As the leading edge of the record-sheet 30 reaches the rear end of the guide-finger 31, it is deflected by a lip 32 of a curved paper-deflector 33 located between the front paper-table 18 and the rear paper-table 14. Due to the curvature of the deflector 33, the leading edge of the record-sheet 30 is deflected upwardly away from the platen, thereby properly directing the sheet toward the rear of the machine and obviating any tendency of said record-sheet from winding around the platen. Due to the fact that the swing-frame 26 is mounted in the platen-carriage 25 only by individually pivoting the end plates 27 to the end frames 24, it is necessary to provide a tie or brace between the side plates of said swing-frame. For this purpose an angle plate 34 extends across the platen between the end plates 27. The ends of the angle plate being preferably bent and overlapped upon one another, as indicated at 35, the overlapped portions thus forming side walls

for attachment to the end plates 27 of the swing frame 26. The end plates are usually fastened to the overlapped portions 35 by rivets 36, as will be readily understood upon consideration of Figure 5. It will be seen, 70 the angle plate 34 includes an upwardly directed wall 37 and a rearwardly extending ledge 38, the front paper-table 18 overlying and fastened to the outer face of said wall 37. Interposed between the angle plate 34 75 and the front paper-table 18, there is a second angle plate 39 having an upstanding wall 39^a and an outwardly extending lip 40, the lip including fingers 41 projecting from the edge thereof and underlying the angle 80 plate 34 at a point adjacent the platen, as clearly illustrated at Figure 1, the purpose of the fingers 41 being to aid the guide-finger 31 in directing the leading edge of the record-sheet 30 to the curved paper-deflector 85 33 during feeding of said record-sheet around the platen. A plate 42 fits against the inner face of the wall 37 of the angle plate 34 and includes out-turned ears 43 which fit snugly against the inner faces of 90 the bent-over portions 35. The plate 42 also includes two outwardly-bent lugs 44 adjacent each end of the plate, the left-hand lug preferably forming a platform upon which the guide-finger 31 is mounted by any suitable means, such as screws 45.

The paper-deflector 33 includes lugs 46 properly spaced to be received and fastened to the lugs 44 of the plate 42, such as by screws 47. The upper portion of the deflector 33 is braced against movement by means of straps 48 adjacent both sides of the table, the straps being provided with fastening feet 49 and secured respectively to the plate 42 and the deflector 33 by any 100 suitable fasteners, screws 50 and rivets 51 being illustrated for this purpose. The plate 42 preferably has upstanding lugs 52 to which one of the feet of each strap 48 is fastened by means of the screws 50. The 105 paper-table 18, and the angle plate 39, the angle plate 34, the plate 42 and the paper-deflector 33, when all fastened together, as shown in section in Figure 1, 110 form a combined tie or strengthening bridge 115 between the side plates of the swing-frame 26. The plates may be all fastened together by screws 53 as will be readily understood by referring especially to Figure 5. Before elevating the platen to strip the carbons from typed sections of the work-plies 120 it is necessary to prevent displacement of the record-sheet. For this purpose a clamping or gripping device in the form of levers 54 is pivoted for swinging movement upon the ears 43 of the plate 42 by means such as screws 55 passing through the levers and into threaded perforations 56 of said ears 43. The lower ends of the levers 54 curve inward toward the paper-deflector 33 125 130

and are preferably bent laterally toward one another at 58 and connected across the platen by a bridge-piece or bail 57 secured to the bent portions of said levers by means of 5 screws 59. Surface-gripping pads 60 of suitable material, such as rubber are carried by the bail 57. Tension springs 61 are effective to cause the levers 54 and the bail 57 to rock as a unit in a direction to press the gripping members 60 against the platen and thereby hold the record-sheet against displacement, when the platen is elevated. The usual hooks 62 for holding the platen-frame in normal position are pivoted at 63 adjacent the rear paper-table 14, the hooks engaging around pins 65 carried by the swing-frame 26, the pins usually comprising anti-friction collars 66 suitably mounted on the end plates 27 by means of screws 67. A finger-piece 64 controls the hooks 62 and is swingable toward the rear of the machine against the action of the usual spring 68 to release the pins 65 from the hooks 62, and thereby permit the swing-frame 26 to throw 25 the platen 15 to an elevated position above the platen-carriage 25.

As it is necessary to hold the record-sheet 30 stationary against displacement prior to elevating the platen, the levers 54 are curved forward, as indicated at 69, and provided adjacent their upper free ends with pins 70, which normally engages the front edges 71 of the hooks 62, to hold the gripping pads 60 off the platen. It will be readily seen by 35 swinging the hooks 62 to release position that the front edges 71 will move away from the pin 70, the spring 61 being effective to rock the levers 54 to force the pads 60 into gripping engagement with the record-sheet. The platen may then be elevated with the record-sheet 30 and the webs 10 straightened beneath the platen, the carbons stripped from the webs and said webs drawn forwardly in the usual manner against a leading-edge 40 gage 72 carried upon a staff 73. Thus it will be observed that the clamping of the record-sheet is entirely automatic in the respect that the only operation necessary to hold said record-sheet stationary is to 45 throw the finger-piece 64 to release position.

Attention is directed to Figure 3 in which the pads 60 have been released by pressure applied to a finger-piece 74 carried by each of the levers 54, thereby permitting the record-sheet 30 to be inserted between the platen and said pads.

With the two wide pinions 22 rotating about an axis fixed to the side frames 24 it is obvious that, when the frame 26 and platen are swung upwardly about the pivots 28, a rotary movement between the two pinions 22 and the platen-gears 21 will take place. The pinions 22 will either roll out of engagement with the stationary platen-gears 21 or the platen-gears will roll out of

engagement with the stationary pinions. The present invention is not concerned with what effect the separation or reengagement of these toothed elements will have upon the platen because the wide surface area of 70 the soft rubber pads against the record-sheet will be effective to hold the record-sheet stationary even if the lifting of the swing-frame effects a slight rotation of the platen. The cohesion between the soft pads and the 75 surface of the record-sheet being greater than the cohesion between the record-sheet and the hard smooth surface of the platen provides that the record-sheet will be held stationary by the pads during the shifting 80 movement of the platen-frame, or by any accompanying rotation of the platen, accidental or otherwise, during the lifting or restoring swing of said platen-frame.

Variations may be resorted to within the 85 scope of the invention, and portions of the improvements may be used without others.

Having thus described my invention, I claim:

1. In a multiple-web typewriting machine, in combination, a revoluble platen, means for elevating the platen that permit work-webs and carbons fed around the platen with a record-sheet, to be straightened prior to effecting relative shifting between said work-webs and the carbons, and normally inoperative means automatically released in elevating the platen for clamping the record-sheet to the platen.

2. In a multiple-web typewriting machine, in combination, a revoluble platen, means for elevating the platen that permit work-webs and carbons fed around the platen with a record-sheet, to be straightened prior to effecting relative shifting between said work-webs and the carbons, and a normally-inoperative cohesive means automatically released in elevating the platen for holding said record-sheet stationary against the platen.

3. In a multiple-web typewriting machine, in combination, a revoluble platen, means for elevating the platen that permit work-webs and carbons fed around the platen with a record-sheet, to be straightened prior to effecting relative shifting between said work-webs and the carbons, and a clamping device including normally-inoperative cohesive ends automatically released by the initial elevation of the platen to hold the record-sheet stationary against the platen during the continued elevation of the platen.

4. In a multiple-web typewriting machine, in combination, a revoluble platen, a swing-frame for elevating the platen that permits work-webs and carbons fed around the platen with a record-sheet to be straightened prior to effecting relative shifting between said work-webs and the carbons, re-

leasable means for holding the platen in normal position, and a normally-inoperative record-sheet clamping device automatically releasable when the platen is released to be elevated, whereby the record-sheet is pressed against the platen to hold the record-sheet stationary during the elevation of the platen.

5. In a multiple-web typewriting machine, in combination, a revoluble platen, a swing-frame for elevating the platen that permits work-webs and carbons fed around the platen with a record-sheet to be straightened prior to effecting relative shifting between said work-webs and the carbons, a clamping device including levers pivoted at each side of said frame and a clamping bar joining the levers together, said bar extending longitudinally of the platen and normally inoperative, and means to automatically release said bar to press the record-sheet against the platen and hold the record-sheet stationary during the elevating movement of the platen.

6. In a multiple-web typewriting machine, in combination, a platen, a table at the delivery side of the platen, means to displace both the platen and table for straightening out continuous work-webs and interleaving carbons prior to stripping the carbons from the work-webs, and a normally inoperative clamp mounted upon the table to be automatically released by the displacement of the platen and table to press one of the webs against the platen in such a manner as to prevent displacement of the web during the carbon-stripping operation.

7. In a multiple-web typewriting machine, in combination, a platen, a table at the delivery side of the platen, means to displace both the platen and table for straightening out continuous work-webs and interleaving carbons prior to stripping the carbons from the work-webs, and a normally inoperative clamp mounted upon the table to be automatically released by the displacement of the platen and table, said clamp having surface-gripping pads operative upon one work-sheet to press the sheet against the platen in such a manner as to prevent displacement of the web during the carbon-stripping operation.

8. In a multiple-web typewriting machine, in combination, a revoluble platen, means for elevating the platen to permit work-webs and carbons fed around the platen with a record-sheet, to be straightened prior to effecting relative shifting between said work-webs and the carbons, and clamping means automatically operable to press the record-sheet to the platen at the beginning of the platen-elevating operation, and automatically releasing the record-sheet when the platen is restored to normal position.

9. In a multiple-web typewriting ma-

chine, in combination, a revoluble platen, means for elevating the platen that permit work-webs and carbons fed around the platen with a record-sheet, to be straightened prior to effecting relative shifting between said work-webs and the carbons, releasable means holding said platen in normal position, a record-sheet-clamping device normally ineffective, and a deflector for guiding the leading edge of said record-sheet under said clamping device and then prevent the record-sheet from winding about the platen, the clamping device being effective to press the record-sheet against the platen adjacent to the edge of the deflector.

10. In a multiple-web typewriting machine, in combination, a platen, a table at the delivery side of the platen, means to displace both the platen and table for straightening out continuous work-webs and interleaving carbons prior to stripping the carbons from the work-webs, and a normally inoperative clamp mounted upon the table to be automatically released by the displacement of the platen and table, to press one of the webs against the platen in such a manner that the line-space position on the web relative to the printing line of the platen will not be disturbed by the shifting movement of the table nor by any accompanying rotation of the platen.

11. In a multiple-web typewriting machine, in combination, a carriage, a revoluble platen, means for elevating the platen to permit work-webs and carbons fed around the platen with a record-sheet, to be straightened prior to effecting relative shifting between said work-webs and the carbons, said elevating means including end plates pivoted to the carriage, the platen being mounted for rotation in said end plates, means for securing said end plates together as a unit, including a tie-bar secured to said end plates and extending across the platen, a front work-table fixed to said tie-bar, guide-fingers extending rearwardly adjacent said tie-bar whereby to guide the record-sheet as it is fed around the platen, a combined work-table and guide directing the record-sheet upwardly and away from the platen and toward the rear of the machine as said record-sheet leaves the guide-fingers, and a clamping device arranged to grip said record-sheet against displacement on the platen at the beginning of the platen-elevating operation.

12. In a multiple-web typewriting machine, in combination, a revoluble platen, means for elevating the platen to permit work-webs and carbons fed around the platen with a record-sheet to be straightened prior to effecting relative shifting between said work-webs and the carbons, said platen-elevating means including side plates in which the platen is journaled, a tie-bar extending across the platen and having the ends

- thereof fastened to said side plates, a front paper-table secured to said tie-bar, a plurality of paper-fingers carried by said tie-bar and extending over the platen, a guiding 5 finger carried by the tie-bar and overlying the platen in conformity to the curvature thereof, whereby to direct the record-sheet to said paper-fingers, a paper-table at the rear of said fingers, said paper-table being curved 10 to direct the record-sheet upwardly and away from the platen as said record-sheet is fed around the platen, beneath the fingers, and a clamping device normally ineffective when the platen is in typing position, said clamping 15 device arranged to clamp the record-sheet against the platen at the beginning of the platen-elevating operation.
13. In a multiple-web typewriting machine, in combination, a carriage, a revolute platen, a swing-frame for elevating the platen above the carriage, and front and rear paper-tables carried by the swing-frame.
14. In a multiple-web typewriting machine, in combination, a carriage, a revolute 25 platen, a swing-frame for elevating the platen above the carriage, said swing frame including side-plates and a tie-bar extending across the platen and connecting the side-plates together, and front and rear paper-tables attached to said tie-bar.
15. In a multiple-web typewriting machine, in combination, a carriage, a revolute platen, a swing-frame for elevating the platen above the carriage, said swing-frame 30 including side plates and a tie-bar extending across the platen and connecting the side-plates together, a front paper-table and a rear paper-table carried by the tie-bar, and a plurality of sheet-deflectors fixed to said tie-bar and so positioned relatively to the rear paper-table that the latter guides the work-sheet upwardly and away from the platen as said work-sheet leaves the deflectors.
16. In a multiple-web typewriting machine, in combination, a revolute platen, 35 means for elevating the platen to permit work-webs and carbons fed around the platen with a record-sheet, to be straightened prior to effecting relative shifting between said work-webs and the carbons, a front paper-table, a rear paper-table, and a combined guide and paper-table intermediate said first-named tables for conveying the record-sheet upwardly and away from the platen as the same is fed therearound. 55
17. In a multiple-web typewriting machine, in combination, a revolute platen, means for elevating the platen to permit work-webs and carbons fed around the platen with a record-sheet, to be straightened 60 prior to effecting relative shifting between said work-webs and the carbons, a front paper-table for supporting the work-webs and carbons, fingers directed rearwardly from said table for guiding the record-sheet 65 toward the rear of the platen, and a curved work-table adjacent the ends of said fingers, whereby to direct the record-sheet upwardly and away from the platen as said record-sheet moves beyond the control of said 70 fingers.
18. In a multiple-web typewriting machine, in combination, a revolute platen, means for elevating the platen to permit work-webs and carbons fed around the platen 75 with a record -sheet, to be straightened prior to effecting relative shifting between said work-webs and the carbons, a front paper-table for supporting the work-webs and carbons, fingers directed rearwardly 80 from said table for guiding the record-sheet toward the rear of the platen, a curved work-table adjacent the ends of said fingers whereby to direct the record-sheet upwardly and away from the platen 85 as said record-sheet moves beyond the control of said fingers, and a clamp for automatically clamping the record-sheet against the platen at the beginning of the platen-elevating operation.

ALFRED G. F. KUROWSKI.
